UNITED STATES PATENT OFFICE.

JESSE W. WITT, OF CINCINNATI, OHIO, ASSIGNOR TO THE WITT CORNICE COMPANY,
OF CINCINNATI, OHIO.

CAN STRUCTURE.

Application filed December 18, 1924. Serial No. 756,676.

To all whom it may concern:

Be it known that I, JESSE W. WITT, a citizen of the United States, and resident of Cincinnati, in the county of Hamilton and State of Ohio, have invented certain new and useful Improvements in Can Structures; and I do hereby declare the following to be a full, clear, and exact description of the invention, such as will enable others skilled in the art to which it appertains to make and use the same.

This invention relates to improvements in can structures and more particularly to means for facilitating the attachment of a bail to the device and the locking of the cover in place, one object of the invention being to provide simple and efficient means whereby the cover of a garbage or ash can may be readily applied to the body of the can and, by a turning movement of the cover, to lock the latter against accidental displacement or removal by animals.

A further object is to so construct fastening means for the cover of a receptacle, that portions of said means may be utilized in effecting connection of a bail with the body portion of the device.

With these and other objects in view, the invention consists in certain novel features of construction and combinations of parts as hereinafter set forth and pointed out in the claims.

In the accompanying drawings,—

Figure 1 is a view in elevation showing a receptacle embodying my improvements, with the cover in locked position.

Figure 2 is a similar view with the cover in unlocked position.

Figure 3 is a sectional view.

Figure 4 is a view showing one of the parts to be secured to the body of the receptacle and a part for cooperation therewith and to be secured to the cover.

In the drawings, I have illustrated the application of my improvement to a garbage can or receptacle, the body portion of which is indicated at 1 and the cover at 2, the latter being provided with a peripheral flange 3, which encircles the upper portion of the body 1, with a handle 4 to facilitate manipulation thereof.

Secured to the body 1 near the upper end thereof and at diametrically opposite positions, are plates 5, the upper portions of which are elongated and provided with out-

wardly projecting flanges 6 having stop lugs 7. The narrower depending portion 8 of the plate 5 is bent so as to form an outward projection or ear 9, while the lower portion of the part 8 lies against the body of the receptacle and is secured thereto by rivet 10 or any other suitable fastening means. The upper portion of each plate also lies against the body 1 and is secured by rivet 11 or other suitable fastening means. The outward projections or ears 9 of the diametrically opposite plate 5 are provided with holes 12 which receive the hooked ends 13 of a bail 14.

To the flanged portion 3 of the cover 2, hook shaped catches 15 are secured at diametrically opposite points. Each of these catches may consist of an elongated plate 16 provided with a depending L-shaped arm 17 so disposed that when the cover is placed on the body 1 and turned, the members 17 will be moved relatively to the plates 5 and the inwardly projecting portions 18 of said members 17 will become disposed under the flanges 6 of said plates. It will be readily understood that turning movement of the cover will be limited by engagement of the portions 18 of the members 17 with the stop lugs 7 and thus the cover will be prevented from being turned far enough in one direction to accidentally disengage the cooperating locking members.

Having fully described my invention what I claim as new and desire to secure by Letters-Patent, is:

1. The combination with a receptacle, and a cover therefor, of a plate secured at its upper and lower ends to the receptacle and having its intermediate portion constructed to be engaged by and secure a bail, the upper extremity of the plate being provided with a laterally projecting flange and a depending transverse stop lug at one end of the flange, and a plate secured to the cover at the margin thereof and having an arm depending downwardly from its lower edge to extend past the edge of the flange on the first-mentioned plate, the lower end of said arm projecting inwardly to engage under said flange and abut the stop lug.

2. The combination with the body portion and cover of a receptacle, said cover having a peripheral flange to receive the upper portion of the body, of diametrically opposite plates secured to the body and each

comprised in a single integral structure having at its upper portion a horizontal outwardly projecting flange and a stop member, each of said plates having an outwardly perforated projection forming a bail ear, said structure secured to the body portion above and below said ear, and catches secured to the flanged portion of the cover and adapt-

ed to be moved into locked relation with the flanged portions of said plates when the cover is turned, the stop members of said plates limiting the turning movement of said cover.

In testimony whereof, I have signed this specification.

JESSE W. WITT
